UNITED STATES PATENT OFFICE.

EMANUEL TOMASZEWSKY AND ROMAN PROCIÓW, OF NEW YORK, N. Y.

AUTOMATIC LEVELING DEVICE.

1,235,259.

Specification of Letters Patent. Patented July 31, 1917.

Application filed December 30, 1916. Serial No. 139,716.

To all whom it may concern:

Be it known that I, EMANUEL TOMASZEWSKY, a subject of the Emperor of Austria, resident of New York, county of New York, 5 and State of New York, and I, ROMAN PROCIÓW, a subject of the Emperor of Austria, resident of New York, county of New York, and State of New York, have invented certain new and useful Improvements in 10 Automatic Leveling Devices, of which the following is a specification.

This invention relates to improvements in furniture, and particularly with reference to tables of a type adapted to be used on 15 board sea going vessels and other like situations where the supporting surface may be subjected to varying inclinations.

The principal object of the invention is to provide a table in which the upper or top 20 portion will at all times remain substantially horizontal irrespective of the position of its supports.

This object is attained by the novel construction and combination of parts hereafter 25 described, and shown in the accompanying drawings, forming a material part of this disclosure, and in which:—

Figure 1 is a bottom plan view of a table made in accordance with the invention.

30 Fig. 2 is a vertical sectional view taken on line 2—2 of Fig. 1.

Fig. 3 is a transverse sectional view taken on line 3—3 of Fig. 1.

Fig. 4 is a perspective view showing the 35 pendulous weight used in maintaining the top of the table in a level position.

Fig. 5 is a perspective view showing an interior corner of the table construction, and

40 Fig. 6 is a partial side elevational view indicating in broken lines some of the various positions which the table elements may assume.

The structure is comprised of a rigid rectangular frame having side and end elements 45 respectively 10 and 11, the same being supported by standards 12 arranged rigidly at the corners thereof. A longitudinal bar 14 is attached rigidly to the end plates 11 and has as its center a bolt 15, in the lower 50 end of which is engaged the elements of a universal joint 16, by means of which the pendent weight 18 is supported.

Formed with the weight 18 upon opposite sides are lugs 19 in which are rigidly 55 secured rods 20, the same extending laterally outward toward the sides of the table where

they are rigidly engaged with yokes 22 at the ends of which are universal joints 23 engaging in turn with tubular elements 25 containing open slots 26. 60

Slidably engaged within the tubes 25 are bars 28 having pins 29 traversable in the slots 26 so that the bars cannot become freed from the tubes. Formed with the outer end of the bars 28 are gear segments 30, rotatable on pins 31, the teeth engaging with the pinions 32 mounted upon shafts 33; alongside and rigid with the pinions are spur gears 35 meshing in turn with pinions 36 secured to shafts 37 which have affixed upon 70 them spur gears 38 engaging with pinions 39 rotatable upon the shafts 40, the opposite side of the pinions engaging with racks 42 attached to and by which the top of the table 45 is supported. The lower side of the table 75 top has attached to it pendant leaves 46, carried by the hinges 47, the leaves acting as guides within the frame whereby the table top is restrained from excessive lateral or longitudinal motion. 80

Thus as the weight or pendulum 18 is oscillated in any direction by reason of its gravity, or more properly if the table assumes other than a horizontal position, the gear connection between the pendulum 85 and the racks are caused to operate, raising or lowering the table top proportionately to the deflection of the supporting surface of the table standards, the top of the table remaining substantially in a horizontal position. 90

When it is desirable to secure the table top rigidly with relation to the frame, as at such times as the vessel is in port or when weights may be placed near the top 95 sliding bars 50 are provided, the same extending upward from the thickened corners of the frame, the bars being moved through the pins 51, rigidly set therein and operable within slots 52 formed in bell-crank 100 levers 53, fulcrumed on pins 54, the other end of the bell-crank levers being pivotally engaged with universal connecting links 55, the outer ends of which engage with the short ends 56 of levers 57, pivoted at 58 in 105 one of the frame members, so that by operating the levers 57 all of the several bars 50 may be raised uniformly and held by friction, thereby holding the table top parallel with the upper edge of the table frame. 110

Casings 60 are provided for the train of gears 30 to 39 inclusive, so as to prevent

dust and the like from gathering therein, and as all the mechanism is contained below the table top, and within the contour of the table frame, with the exception of the pendulum weight, there is nothing objectionable in the appearance of the device which resembles an ordinary dining table.

The operation of the device is thought to be evident from the foregoing description from which it will be seen that the purpose or object desired is met in a practical manner.

Having thus described our invention, what we claim as new, and desire to secure by Letters Patent, is:—

1. In a table of the class described, the combination with a rigid frame, and supports therefor, of a bar centrally disposed longitudinally of said frame, a weight suspended at the center of said bar, a table top, rack supports engaging with said top, and means operable by said weight for actuating said supports whereby the said table top is maintained in a horizontal position irrespective of the supports of the table frame.
2. In a table of the class described, the combination with a rigid frame having sup-

ports at the corners thereof, a pendent weight pivotally attached centrally of said frame, a cover loosely engaged with said frame, vertical racks attached to said cover extending downward within said frame, a gear train engaged with said racks, and means combined with said pendent weight for actuating said gear train when said weight is caused to move in any direction.

3. In a table of the class described, the combination with a rigid rectangular frame having corner supports, a table top loosely engaged within said frame, a weight supported by said frame, means permitting said weight to oscillate in any direction, arms rigidly engaged with said weight, yokes on the ends of said arms, a gear train, means for actuating said gear train engaged with said yokes, and means combined with said gear train for raising or lowering portions of said table top according to the inclination of the said weight.

In testimony whereof we have affixed our signatures this 1st day of December, 1916.

EMANUEL TOMASZEWSKY.
ROMAN PROCIÓW.
